UNITED STATES PATENT OFFICE.

STACY B. HASELTINE, OF CHICAGO, ILLINOIS, ASSIGNOR, BY MESNE ASSIGNMENTS, TO
W. H. MINER, INC., A CORPORATION OF DELAWARE.

DOOR OPERATING AND LOCKING DEVICE.

Application filed December 31, 1923, Serial No. 683,552. Renewed September 8, 1925.

To all whom it may concern:

Be it known that I, STACY B. HASELTINE, a citizen of the United States, residing at Chicago, in the county of Cook and State 5 of Illinois, have invented a certain new and useful Improvement in Door Operating and Locking Devices, of which the following is a full, clear, concise, and exact description, reference being had to the accompanying 10 drawings, forming a part of this specification.

This invention relates to improvements in door operating and locking devices.

One object of this invention is to provide 15 a simple, efficient and inexpensive device which is applied to a door of the sliding type and which has effective means for either drawing the door tightly closed or starting the opening operation thereof and which 20 also serves as a device for locking the door either tightly closed or in partly opened position.

More specifically an object of this invention is to provide a device of the character 25 described, wherein toggle lever operating mechanism is employed to force the door to tightly closed position or start the opening operation thereof.

In the drawing forming a part of this 30 specification, Figure 1 is a side elevational view of a portion of a box car, showing a portion of the sliding door thereof with my improvements in connection therewith. Figure 2 is a horizontal, sectional view corresponding substantially to the line 2—2 of Figure 1. Figure 3 is a view similar to 35 Figure 2 showing in full lines the position of the parts with the door partly opened and illustrating in dotted lines the position 40 of the parts when the door is locked in partly opened position thereby. And Figure 4 is a vertical, sectional view corresponding substantially to the line 4—4 of Figure 1.

In said drawing, 10 denotes the sliding 45 side door of a railway box car and 11 the side wall of said car. One of the door posts is indicated at 12 in Figures 2 and 3, the same being cut away at its outer side to provide a door stop 13 against which is adapted 50 to bear the front edge of the door when the same is in fully closed position.

The improved door operating and locking device, as shown, comprises broadly, a bracket A; a bearing plate B; a link supporting member C; a strap D; a link E; an

operating handle lever F; and a latch plate G.

The link supporting member C is in the form of a relatively heavy rectangular plate having an inner flat face bearing on the 60 plate B interposed between the same and the outer side of the door. The bearing plate B is of substantially square outline, as clearly shown in Figure 1, and is fixed to the door by means of screws or any other 65 suitable securing devices. The plate B is of such a size as to provide a full bearing surface for the plate C in all operative positions thereof. At the side opposite to that abutting the plate B, the plate C is formed 70 with a cylindrical boss 15 spaced inwardly from the end of the plate and working in an opening 16 provided in an outwardly offset portion 17 of the strap D, the strap D being horizontally disposed and secured to 75 the door by means of a pair of bolts 18—18. The plate C is rotatably mounted on the bearing plate B by a bolt 19 extending centrally through the boss 15, the plate B and the door 10, and projecting through the 80 opening 16 of the plate D, a washer 20 being interposed between the head of the bolt and the outer side of the offset portion 17 of the strap. At the free end the plate C is provided with an outstanding lateral enlargement 21 of substantially cylindrical 85 form extending transversely of the same. The enlargement is provided with an axial bore adapted to receive a pivot pin 22.

The link E comprises a pair of parallel 90 spaced arms 23 connected by an integral longitudinally disposed central web 24 having its opposite edges spaced inwardly from the corresponding ends of the arms. The projecting portions of the arms at one end of 95 the link E are disposed on opposite sides of the projection 21 and are provided with alined openings adapted to receive the pivot pin 22. The link is thus pivotally connected to the supporting member C, the projecting 100 opposite ends of the pin 22 being headed over to retain the parts in assembled relation. The projecting portion of the arms 23 at the opposite end of the link E are also provided with alined pin receiving openings 105 25.

The operating lever F is in the form of an elongated bar having a hand grip 26 formed at the free end thereof. From the inner end of the hand grip to its opposite 110

end, the lever is composed of two longitudinally extending, spaced parallel sections 27—27, the free ends of the sections being connected by a transversely disposed, cylindrical fulcrum member 28 formed integral with the sections. A second transversely disposed, integral connecting member 29 is disposed between the sections 27 inwardly of the fulcrum member 28. The member 29 5 has a flat face 30 disposed in a plane substantially at right angles to the longitudinal axis of the lever and a flat face 31 at the opposite side thereof inclined with reference to the face 30. The member 29 is laterally extended beyond the plane of the side of the handle portion of the lever, and each section 10 27 is laterally enlarged to correspond therewith as indicated at 32 thereby providing an offset portion in each section. As clearly 15 shown in Figures 2 and 3, each of the sections is tapered from the offset portion to the fulcrum end of the lever, thereby providing a side edge 34 inclined with reference to the longitudinal axis of the lever. The 20 projecting portions of the arms 23 at the end of the link opposite to its connection with the plate C embrace and are pivotally connected to the offset portion of the lever F by a pivot pin 35 extending through the 25 offset portions 32 of the sections 27, the member 29 and the openings 25. It will be evident that the lever and link E are joined in the manner of a toggle and that the link E is pivotally connected to the lever 30 at one side of the longitudinal axis thereof. To limit the relative movement of the lever F and the link E so as to prevent the toggle 35 from being straightened, the web 24 of the link E is provided with a laterally projecting lug 36 having an inclined face adapted to form an abutment coacting with the correspondingly inclined edge 34 of the lever F. The stop bracket A is in the form of a plate applied to the door stop 13, the same 40 having three spaced lateral flanges 37—37, two of which extend along the front and rear edges of the door stop 13. The third flange serves as a brace between the plate and the side wall of the car, as clearly shown 45 in Figures 2 and 3. At the lower side the plate is provided with an inwardly offset portion 38 adapted to lie flat against the side wall of the car, the same being secured to the side wall by a bolt or any other suitable 50 device. The bracket A is also secured to the door stop by means of bolts extending through the plate portion thereof. Adjacent the upper and lower edges of the plate 55 outwardly projecting flanges 39 are provided, the same being spaced apart a proper distance to loosely receive the lever F and the link E therebetween. As clearly shown in Figure 4, the plates 39 are curved at their outer ends, thereby providing a flaring opening 60 facilitating entrance of the link and lever therebetween. The lower flange 39 extends longitudinally beyond the upper flange as clearly shown in Figure 1 and is provided at its outer edge with a relatively short upstanding flange 40. The upper surface of the lower flange 39 is also provided with a transversely disposed rib 41 connecting with the flange 40. Between the flanges 39, the flat portion of the bracket A is provided with a pair of outstanding spaced projections 42 and 43 adapted to coact with the fulcrum member 28 of the lever F. The projection 42 is cut away at its inner side as indicated at 44, thereby providing a rounded bearing surface for the fulcrum member 28 and an overhanging hook portion preventing disengagement of the fulcrum member from the projection. The projection 43 is provided with a substantially straight inner face 45 adapted to coact with the fulcrum member of the lever. It will be noted that the bearing surface of the projection 42 and the surface 45 of the projection 43 are spaced apart a greater distance than the diameter of the fulcrum member 28, thereby permitting limited movement of the member 28 within the opening between the projections. The overall distance between the outer sides of the projections 43 and 44 is slightly less than the opening 95 provided between the face 30 of the member 29 and the inner end of the handle portion of the lever F, so that the lever may be placed in position over the lugs which are entered into the opening, the same acting as 100 a locking means to prevent movement of the lever in a longitudinal direction. The latch plate G is provided with an opening 46 at its upper end adapted to receive a bolt 47 whereby it is pivotally connected to the upper portion of the bracket A. The plate G is adapted to swing in a vertical plane and is of such a length as to extend behind the flange 40 when in its depending position. Along the edge of the plate G adjacent the rib 41, a vertically extending flange 48 is provided adapted to abut the rib 41 and limit the swinging movement of the plate. At its lower end, the plate also has a horizontally disposed flange 49 provided with a lock receiving opening 50. The lower flange 39 of the bracket A is provided with a corresponding lock receiving opening, with which the opening 50 is adapted to be aligned when the plate G is 115 disposed in the full line position shown in Figure 1. Aligned openings in latch G and lower flange 39 are also provided for receiving the usual car seal. Assuming that the parts are in the position shown in full lines in Figures 1 and 2 of the drawing, when it is desired to open the door, the following sequence of operations are performed. The seal is first removed, after which the pivoted plate G is 120 125 130

swung upwardly to the dotted line position shown in Figure 1. The operating lever F is then swung outwardly, thereby causing the same to swing on its pivotal connection with the link E until the fulcrum member 28 engages with the face 45 of the projection 43, whereupon the lever will swing upon the fulcrum as a pivot pushing the door open until it reaches the position shown in full lines in Figure 3. It will be evident that during this operation, the lever and link act as a toggle mechanism thereby greatly multiplying the force applied during the initial portion of the operation. The movement of the lever in the door opening operation will be arrested by engagement of the edge 34 with the flat front face of the plate portion of the bracket A. When the door has thus been opened, the fulcrum member is disengaged from between the projections 42 and 43 and dropped to the dotted line position shown in Figure 1, the plate C turning freely on the plate B and the lever swinging on its pivot 35 under the influence of gravity. If it is desired to lock the door in the partly opened position in Figure 3, the lever is swung on the pivot 35 until it assumes the dotted line position shown in Figure 3 and is engaged over the projections 42 and 43, the link E resting on the lower flange 39 of the bracket A, thereby supporting the lever F. The pivoted plate G is then swung from the dotted line position shown in Figure 1 to the full line position, thereby holding the lever securely in place. The parts may then be properly sealed by fastening the usual car seal within the openings in the member G and the flange 39. When it is desired to close the door, the latter is moved to a point as near the door stop 13 as can be conveniently done by the operator, which may be substantially the position shown in Figure 3. Thereupon the operator swings the handle from the dotted line position shown in Figure 1 to a horizontal position and enters the fulcrum member 28 into the space between the projections 42 and 43. Upon pulling the handle end of the lever outwardly, the fulcrum member 28 will be brought into engagement with the curved bearing surface on the inner side of the projection 42 where, upon further movement of the lever F, the same will pivot on the fulcrum member 28 thereby drawing the link E toward the stop 13 and pulling the door closed, which position is indicated in full lines in Figure 2. As hereinbefore pointed out, movement of the lever F relatively to the link E will be limited by engagement of the inclined face of the lever with the lug 36 on the link, thereby preventing the toggle from being overthrown and straightened out. After the lever has reached the position shown in Figure 2, the latch G is dropped in front

of the same and the usual car seal applied through the registering openings of the plate G and the flange 39.

Although I have herein shown and described the plate A as secured to the door post and the other parts as fastened to the door, it will be understood that the position of the parts may be interchanged without departing from the spirit of the invention.

I claim:

1. In an operating and locking mechanism for a sliding door, the combination with a fixed abutment member; of toggle means adapted to be detachably connected with said abutment for operating the door, 70 said means being supported entirely on the door and including a hand operating lever movable in a horizontal plane engageable with said abutment to hold the door in fixed position; and means for locking said lever to said abutment when engaged therewith to hold the door in closed position.

2. In an operating and locking mechanism for a sliding door, the combination with an abutment member; of toggle means 90 adapted to be detachably connected with said abutment for operating the door, said means including an operating lever movable in two different planes; and cooperating means on said lever and abutment for locking said door in two different positions.

3. In an operating mechanism for a sliding door member associated with a frame member, the combination with an abutment element fixed to one of said members; of 100 toggle means mounted on the other member, said toggle means including a link and an operating lever, each movable in two different planes, said operating lever having means thereon for detachably connecting the 105 same to said abutment element.

4. In an operating mechanism for a sliding door member associated with a frame member having a door opening therein, the combination with a bracket fixed to one of 110 said members having abutment means thereon; of toggle means bodily swiveled on the other member and adapted to assume a pendant position under the influence of gravity, said means including a link and a lever, said lever being pivoted to the link for movement laterally of said door; and a fulcrum element on said lever adapted to be detachably engaged with the abutment means of said bracket, whereby upon operation of said lever in one direction the door member is forced open and upon operation of said lever in the reverse direction, the door member is pulled tightly closed.

5. In an operating mechanism for a sliding door member associated with a frame member, the combination with an abutment element fixed to one of said members; of 120 toggle means carried by the other member, said toggle means including a head swiv- 125

130

eled on the last named member, a link pivoted to said head, and an operating lever having a fulcrum element at one end thereof adapted to detachably engage said abutment element, said lever being pivoted to said link inwardly of the fulcrum element thereof.

6. In an operating and locking mechanism for a sliding door member associated with a frame member, the combination with an abutment element fixed to one of said members; of toggle means carried by the other member, said toggle means including a head swiveled on said last named member, a link pivoted on said head and an operating lever having a fulcrum element at one end thereof adapted to detachably engage said abutment element, said lever being pivoted to said link; and means for locking 20 said door in two positions, said means including inter-engaging elements on said abutment means and lever.

7. In an operating mechanism for a sliding door member associated with a frame member, the combination with a pair of abutment elements fixed to one of said members; of a toggle mechanism mounted on the other element, said toggle mechanism including a lever having a pair of arms, and 30 an integral fulcrum member between said arms adapted to be detachably connected with said abutment elements, said fulcrum element being brought into forcible engagement with one of said abutment elements upon movement of said lever in one direction to close the door tightly and adapted to be brought into forcible engagement with the other abutment element upon reverse movement of the lever to effect an opening 40 movement of said door member.

8. In an operating mechanism for a sliding door member associated with a frame member, the combination with a pair of spaced abutment elements fixed to one of said members, one of said elements having an overhanging projection thereon; of a toggle mechanism mounted on the other member, said toggle mechanism including a lever having a fulcrum member thereon adapted to be detachably connected with said abutment elements, said fulcrum element being brought into forcible engagement with said element having the projections thereon, upon movement of said lever in one direction to tightly close the door and

adapted to be brought into forcible engagement with the other abutment element upon reverse movement of the lever to effect an opening movement of said door member; and means for locking said lever in position 60 to hold the door tightly closed.

9. In an operating and locking mechanism for a sliding door member associated with a frame member having a door opening therein, the combination with a pair of abutment elements fixed to one of said members; of a toggle mechanism mounted on the other member, said toggle mechanism including a lever having fulcrum means at one end thereof adapted in one position of the lever 70 to be engaged between said abutment elements to hold the door tightly closed, said lever being also provided with an opening adapted in another position of the lever to receive said abutment elements to hold the 75 door partly opened; and locking means for retaining the lever in either of said positions.

10. In an operating and locking mechanism for a sliding door member associated with a frame member having a door opening therein, the combination with a pair of abutment elements fixed to one of said members; of toggle mechanism mounted on the other member, said toggle mechanism including a lever having fulcrum means at one end thereof coacting with said abutment elements, said lever being also provided with an opening adapted in one position of the lever to receive said abutment elements to 80 hold the door in partly opened position; and locking means for retaining said lever in said position.

11. In an operating mechanism for a sliding door member associated with a frame member, the combination with an abutment element fixed to one of said members; of toggle means mounted on the other member, said toggle means including a link and an operating lever, said operating lever having 95 means thereon for detachably connecting the same to said abutment element; and coacting abutment means on said link and lever adapted to limit the relative movement thereof to prevent straightening of the toggle joint.

In witness that I claim the foregoing I have hereunto subscribed my name this 24th day of December 1923.

STACY B. HASELTINE.
